(57) **CLAIM**

The ornamental design for a spectacle case, as shown and described.

DESCRIPTION

FIG. 1 is a top perspective view of a spectacle case, showing our new design in a closed configuration;

FIG. 2 is a top plan view thereof;

FIG. 3 is a front elevation view thereof;

FIG. 4 is a right side elevation view thereof, the left side being a mirror image thereof;

FIG. 5 is a right side elevation view of the spectacles case of FIG. 1 in an open configuration;

FIG. 6 is a top perspective view thereof;

FIG. 7 is a top plan view thereof;

FIG. 8 is a bottom plan view thereof;

FIG. 9 is a bottom plan view of the spectacles case of FIG. 1 in the closed configuration;

FIG. 10 is a rear elevation view thereof;

FIG. 11 is a top perspective view of another embodiment in a closed configuration thereof;

FIG. 12 is a top plan view thereof;

FIG. 13 is a front elevation view thereof;

FIG. 14 is a right side elevation view thereof, the left side being a mirror image thereof;

FIG. 15 is a right side elevation view of the spectacles case of FIG. 11 in an open configuration;

FIG. 16 is a top perspective view thereof;

FIG. 17 is a top plan view thereof;

FIG. 18 is a bottom plan view thereof;

FIG. 19 is a bottom plan view of the spectacles case of FIG. 11 in the closed configuration; and,

FIG. 20 is a rear elevation view thereof.
